UNITED STATES PATENT OFFICE

EDWARD A. HOBART, OF TROY, OHIO, ASSIGNOR TO THE HOBART BROS. COMPANY, OF TROY, OHIO, A CORPORATION OF OHIO

DESIGN FOR A CAR-WASHING PUMP

Application filed September 16, 1930. Serial No. 36,987. Term of patent 7 years.

To all whom it may concern:

Be it known that I, EDWARD A. HOBART, a citizen of the United States, residing at Troy, in the county of Miami and State of Ohio, have invented a new, original, and ornamental Design for a Car-Washing Pump, of which the following is a specification, reference being had to the accompanying drawing, forming a part thereof.

In the accompanying drawing:

Figure 1 is a side elevation of the car washing pump, showing my new design;

Figure 2 is a top plan view thereof;

Figure 3 is an end elevation thereof.

I claim:

The ornamental design for a car washing pump, substantially as shown.

EDWARD A. HOBART.
